UNITED STATES PATENT OFFICE.

JOHN H. FLAGLER, OF NEW YORK, N. Y., ASSIGNOR TO THE NATIONAL TUBE WORKS COMPANY, OF BOSTON, MASSACHUSETTS.

VEHICLE-AXLE.

SPECIFICATION forming part of Letters Patent No. 444,065, dated January 6, 1891.

Application filed December 24, 1888. Serial No. 294,454. (No model.)

To all whom it may concern:

Be it known that I, JOHN H. FLAGLER, of New York city, county and State of New York, have invented certain new and useful 5 Improvements in Axles, of which the following is a specification.

This invention pertains to improvements in tubular vehicle-axles. Tubular vehicle-axles are at once light and strong, and by reason of their tubular construction they possess a certain degree of elasticity, permitting a limited degree of yielding without involving strains liable to lead to breaking. Where the bar is subjected to deflective strains and 15 the elastic yielding of that bar is depended upon to a certain extent to prevent the imposition of short disintegrating bends, it is highly important that the waves of flexure should be free to traverse throughout the 20 length of the portion of the bar subjected to the strain. The principle may be best illustrated in the railroad-track in which a wave of flexure is produced by the movement of the traveling load, the elasticity of the track 25 permitting the flexure. The problem in constructing the joints of the rails is not to secure extraordinary stiffness, but to secure the proper strength without interfering with that degree of flexibility normal to the body of 30 the rail. Extra stiffness at the joints results in damage by breaking at the joints, while a weaker joint would permit the forward movement of the flexure wave without destructive effects.

35 In tubular axles it is highly important to employ transverse partitions within the axle to partition off the cavities of the end portions of the axles from the central cavity in the body of the axle, the end cavities 40 being employed for the holding of lubricants. The partitions employed have generally consisted of rigid unyielding blocks or cups inserted within the axle. These cups or blocks have resulted in giving the axles an extraordinary 45 stiffness at the partition-points, and experience has developed the fact that these extra strong points in the axle are the points at which breaks are quite liable to occur.

50 My invention has to do with the provision of an axle with elastic partitions avoiding the

extraordinary stiffening of the axle at the partition-points.

My improvements will be readily understood from the following description, taken in connection with the accompanying drawings, in which—

Figure 1 is a side elevation of a tubular axle illustrating my improvements, the right-hand portion of the axle appearing in this view in vertical longitudinal section; Fig. 2, 60 a vertical longitudinal section, upon an enlarged scale, of a portion of the axle with its elastic partitions; Fig. 3, a vertical transverse section of the same, exhibiting the elastic partition in elevation; and Fig. 4, a face 65 view of the elastic partition before being given its final shape.

In the drawings, A indicates the tubular body of the axle; B, the tubular spindle portions thereof, provided at their outer ends 70 with nipples for the reception of the wheel-keepers; C, the usual collars at the juncture of the body portion with the spindle portions, these collars forming the inner end bearing or thrust-bearings for the wheel-hubs, and 75 serving, also, in general construction, as means for attaching the axle to the appropriate parts of the vehicle; D, elastic partitions inserted within the tubular axle near the collars and serving to divide the cavity of the axle into 80 three parts—namely, the central body cavity and the two spindle-cavities—these partitions being in the form of a cup whose periphery fits and fills the bore of the axle; and E, longitudinal slits in the periphery of the cup- 85 like partition.

The partitions are to be made of non-rigid material, preferably of wrought-iron or steel sheet metal. In practice I make them by punching out a piece of metal of the general 90 form illustrated in Fig. 4. From the blank thus formed I strike up the cup of such diametrical dimension that it will fit snugly in the bore of the axle without the slits E becoming entirely closed. The cups thus possess a diametrical elasticity, and do not to 95 any material degree interfere with the elasticity of the axle at their points of insertion.

If the axles have their outer ends reduced in diameter, as illustrated in Fig. 1, and as is 100

the general practice, it is obviously necessary that the partitions be inserted in place before the end reductions are performed.

I claim as my invention—

5 In an axle, the combination, substantially as set forth, of the tubular body and end portions of the axle and the elastic cup-shaped

transverse partitions formed with peripheral slits.

JOHN H. FLAGLER.
